CHAMBER POT

Roy Aitken, Glasgow, Scotland

Application January 28, 1949, Serial No. 535
In Great Britain December 29, 1948

Term of patent 14 years

(Cl. D4—3)

To all whom it may concern:

Be it known that I, Roy Aitken, a subject of the King of Great Britain and a resident of Glasgow, Scotland, have invented a new, original, and ornamental Design for a Chamber Pot, of which the following is a specification, reference being had to the accompanying drawing, forming part thereof.

Fig. 1 is a perspective view from one side and above of a chamber pot, showing my new design.

Fig. 2 is a perspective view from below and from the other side of the pot shown in Fig. 1.

Fig. 3 is a sectional view on the line 3—3 of Fig. 1.

I claim:

The ornamental design for a chamber pot, as shown.

ROY AITKEN.
